UNITED STATES PATENT OFFICE.

ALVIN F. PAINE, OF SOUTH WELLFLEET, MASSACHUSETTS; ISAAC PAINE
ADMINISTRATOR OF SAID ALVIN F. PAINE, DECEASED.

STORM-RIG FOR VESSELS.

SPECIFICATION forming part of Letters Patent No. 435,568, dated September 2, 1890.

Application filed January 11, 1890. Serial No. 336,688. (No model.)

To all whom it may concern:

Be it known that I, ALVIN F. PAINE, of South Wellfleet, county of Barnstable, State of Massachusetts, have invented an Improvement 5 in Storm-Rigs for Vessels, of which the following description, in connection with the accompanying drawings, is a specification, like letters and figures on the drawings representing like parts.

10 This invention relates to a novel storm-rig for vessels, and is especially adapted to be used in place of the usual rig on fore-and-aft-rigged vessels, either steam or sail, in stormy weather.

15 In accordance with my invention I employ a stay-band, which may be made of sufficient size to encircle the mast, or which may be made small enough to slip over a stay rope or rod. When applied to the mast, the stay-band 20 will preferably be made detachable, and may be secured aloft by means of a suitable halyard rove through a suitable pulley-block, and adapted to be secured at the foot of the mast or to the deck in any usual manner.

25 The stay-band on the mast has fastened to it on one side of the mast one end of a stay rod or rope, which may be fastened at its other end to a second mast or to the deck or other part of the vessel, and upon which may be secured a stay-sail, as will be described, and the

30 said stay-band may have attached to it on the other side of the mast one end of a second stay, having its other end secured to the foot of the mast or to the deck, and, if desired, a try-sail may be secured on the said stay. The stay-band when used on a stay rod or rope may support a yard, upon which may be set a sail to obtain on a fore-and-aft-rigged vessel the advantages now possessed by a square-rigged vessel, as will be described.

35 The particular features of my invention will be pointed out in the specification, and specified in the claims at the end thereof.

Figure 1 represents a three-masted vessel 45 provided with my improved rig; Fig. 1^a, a three-masted vessel, showing the yard-sail on the foremast only; Fig. 2, a three-masted vessel with storm-sails set, as when "on the wind;" Fig. 3, a three-masted vessel with 50 storm-sails set, as when "running off free from

the wind." Fig. 4 represents a schooner riding at a drag or anchor. Fig. 5 represents a stern view of a vessel to more clearly show the yard secured to the stay-band. Fig. 6 is a detail, on an enlarged scale, of a portion of 55 a mast with the form of stay-band preferred by me; Fig. 7, a detail, on an enlarged scale, to more clearly show the stay-band to which a yard is secured, the stay rod or rope and the stay-band being shown in a horizontal 60 position, which is substantially at right angles to its proper working position; Fig. 7^a, a side view of the rig shown in Fig. 7, the stay rod or rope being shown in its proper position; Fig. 8, a detail in section and elevation, 65 on an enlarged scale, of a hook secured to or forming part of the stay-band used on the mast; Fig. 9, a detail in section and elevation, on an enlarged scale, of the modified form of hook; Fig. 10, a detail to be referred to; Fig. 70 11, a top or plan view of the stay-band shown in Fig. 6; Fig. 12, a modified form of stay-band; and Fig. 13, a detail, on an enlarged scale, of the yard and its sail to more clearly show the manner of working the sail. 75

The vessel A (shown in Figs. 1, 1^a, 2, and 3 as provided with a foremast a, mainmast a', and mizzen-mast a², and in Fig. 4 with a main-mast a' and foremast a) may be of any usual or well-known construction common to fore-and-aft-rigged vessels. The vessel A is provided with the usual working-sails, such as now commonly used on vessels of this class, but of which only the forestay-sail a³, jib a⁴, and flying jib a⁵ are shown in Figs. 2 and 3. 80 85

In accordance with my invention I have provided a stay-band, which may be placed upon or made to encircle each or any mast or a stay. This stay-band when used on the mast will preferably be made in two parts a⁵ 90 a⁶, detachably secured together. Each part a⁵ a⁶ of the stay-band, as herein shown, (see Fig. 11,) is bent or shaped to partially embrace the mast, the said parts being so constructed as to be connected together in a detachable manner. As herein shown, each of said parts is shaped to constitute arms 2 3 and leave shoulders 4 5 and an eye or loop 6. The shoulders 4 5 support the opposite ends of a bolt or rod a⁷, on which is mounted an 100

anti-friction device. (Shown as a block a^8 , but which may be a roller.) The parts a^5 a^6 of the stay-band may be secured together by means of hooks a^9 on the ends of the arms 23 of one 5 or both parts a^5 a^6 of the stay-band, the said hooks preferably engaging a link a^{10} . The stay-band is shown as loosely mounted on the mast, and may be hoisted aloft on the mast by a halyard b , (see Figs. 1 and 6,) secured, as 10 herein shown, to one eye b' of a hook or bent link b^2 , encircling the eye b of the part a^6 of the stay-band, and provided with a second eye b^3 , to which one end of a stay rod or rope b^4 is hooked or otherwise secured; but the 15 halyard might be attached directly to the eye b . The eye b of the other part a^5 of the stay-band has secured to it, as by a hook b^x , one end of a stay rope or rod b^5 . The halyard b may be the usual throat-halyard, which in 20 practice may be readily detached from the gaff and secured to the eye b' . The lower end of the stay b^4 is secured to the deck or other part of the vessel, and the stay b^5 may have its lower end secured to the foot of the mast 25 forward of the mast on which the stay-band is placed or to the deck. Each stay b^5 may have secured or rigged upon it a sail c , substantially triangular in shape and called the "stay-sail," and the said sail may be hoisted in 30 usual manner by means of a halyard c^x , (see Figs. 1 and 6,) connected to the stay-sail by usual pulley-blocks c^{10} , which may be secured to the stay-band or to the stay b^5 , so that when the stay-band is hoisted aloft the stay b^5 and halyard c^x will be sent aloft at the 35 same time. The stay b^4 may have secured to it a sail c' , called the "try-sail," which may be hoisted by a suitable halyard c^{12} , rove through pulley-blocks c^{13} , secured to the stay-band, as shown in Fig. 6, or to the stay b^4 .

Referring to Figs. 1 and 1^a, the try-sail c' and stay-sail c on the mizzen-mast are shown as set, and in Figs. 2 and 3 the try-sails c' and stay-sails c on the main and mizzen masts and the try-sail on the foremast, together with the forestay-sail a^3 , jib c^4 , and flying jib c^5 of the usual rig, are shown as set.

I have thus far described the stay-band as placed on the mast; but, if desired, it may be 50 mounted on a stay rope or rod d , which may be one of the usual stays of the vessel or an independent stay secured at one end to the stay-band on the mast, as shown in Figs. 1 and 1^a, or secured aloft in other usual manner. The stay-band placed upon the stay referred to may be made as a collar d' , (see Fig. 7,) slipped over the stay at its lower end, the said stay-band or collar having secured to it one or more rings or eyes d^2 , which support a 55 yard d^5 , herein shown as secured to the rings or eyes d^2 by ropes d^3 d^4 , the said ropes, as herein shown, being passed through eyebolts d^6 d^7 on the yard. The yard d^5 has fastened to it a second stay band or collar d^x , (see 60 Figs. 1 and 7^a,) which may be similar to the stay-band d' , and through which the stay d is passed, and the said yard in practice is

also fastened to the deck by a check-stay d^{10} . The yard d^5 may be raised and lowered independently of the sail by means of a halyard e , which may be one of the usual halyards, or it may be an independent halyard, the said halyard being rove through usual pulley-blocks e^x , (see Fig. 1,) secured to a ring e' on the upper stay-band d' , so that the yard may 70 be raised and lowered independently of the sail and the stay d , the check-stay d^{10} limiting the upward movement of the yard. The ropes d^3 d^4 , as shown in Fig. 7, form two substantially right-angled triangles, and the yard-sail d^8 at its apex is provided with a ring e^5 , (see Fig. 13,) through which the upright portions of the said ropes are passed, and the said ring may be secured by a halyard to a pulley-block e^6 , connected to the ring e^5 and 80 stay-band, so that the sail d^8 may be operated from the deck, the said sail being first secured to the yard-arms. The yard, as shown in Fig. 1^a, has secured to its arms sheets or braces d^7 d^8 , by which the said yard may be trimmed 85 or set, as desired.

My improved rig is designed to be used in stormy weather, and can easily be substituted for the regular rig, which will allow the large sails to be snugly furled and the booms and 90 gaffs secured, thus saving them from the wear and tear to which they are subjected, especially in a gale. In the storm-rig only such sails as are needed are exposed, and as these are triangular in shape and have no heavy 100 booms to support they are less liable to damage than a reefed boom and gaff-sail, and if one should be blown away another could readily be put in its place. They can be set where they are most needed and at a sufficient 105 height from the deck not to lose the force of the wind when in the hollow of the sea, thus enabling the vessel not only to lie close to the wind, but steadily and with increased safety. Their size and arrangement 110 are such that they can be handled from the deck by a small crew, and in case of danger ahead the helm can be put "hard up" and the halyards of the aftersails be cast off or loosened, so that the vessel will then fall off 115 quickly and thus be likely to escape serious disaster, and if necessary to "jibe ship" there will be no danger of broken spars or torn sails. Sometimes a gale moderates very suddenly, leaving the vessel to roll so heavily 120 that under the usual rig the sails have to be taken in to save them and the spars from damage. The vessel will then lie helplessly in the trough of the sea, while under the storm-rig, with no booms or gaffs to throw the 125 wind out of the sails, she would lie more safely and perhaps be able to make some progress on her course. Under this rig the danger of losing the masts is much lessened, as the setting up of the stays forward from 130 the main and mizzen masts gives them support at their weakest point, as in the usual rig the said masts depend wholly for their forward support on the spring-stays, which

all lead to the foremast-head, and if this is broken off or the stay gives way at this point, as it is liable to do when plunging into a head-sea, the masts are left without support 5 and soon go crashing over the side, whereas with my improved rig each mast is supported forward by a separate stay running to the deck and independent of the spring-stays. In running off free from the wind all of the 10 sails, except the mizzen try-sail, could be reversed—as, for instance, the mizzen stay-sail c in Fig. 2 would be the main try-sail in Fig. 3, and the main stay-sail in Fig. 2 would be the fore try-sail in Fig. 3, and the main try-sail in 15 Fig. 2 would be the mizzen stay-sail in Fig. 3, and the fore try-sail in Fig. 2 would be the main stay-sail in Fig. 3. When running off free from the wind, the masts do not need the forward support, and therefore the stays may 20 be carried off to one side of the vessel, as to the rail.

The hook a^9 , preferably made as shown in Fig. 8, consists of a bent or curved rod having a threaded shank 20, upon which is loosely 25 fitted a collar 21, having a post 22, provided, as herein shown, with a pin 23 adapted to enter a pocket or hole 24 in the end of the curved rod and be locked therein by a nut 25, engaging the threaded shank 20. The nut 30 25 is provided with a lug or ear 27, having a hole 28, into which enters a spring-actuated rod 29, the said rod being located in a socket or recess in the post 22 and normally pressed outward, as shown by the spring 30 encircling the said rod. The rod 29 is limited in 35 its outward movement by a cross bar or rod 31, extended through slots 40 in the sides of the post 22. (See Fig. 10.) The spring-actuated rod 29 forms a locking device for the 40 hook, and prevents the post from becoming disconnected from the bent rod. I prefer to construct the hook as shown in Fig. 8; but it may be constructed as shown in Fig. 9, wherein the shank of the rod is provided 45 with a square or other than round section, as at 50, upon which is fitted the square or other than round collar 51, provided with a post 22, having as shown, a pin 23. The square shank-section 50 and its co-operating 50 square collar form the locking device for the hook to prevent the post 22 from swinging round to open the hook. The hook a^9 may, and preferably will, have its shank 20 turned or bent substantially at right angles to the 55 hook to form an eye, (see Fig. 12,) which is engaged by two links $f^2 f^3$, to one of which a stay-rod may be connected and to the other

of which a halyard may be connected, and when made as shown in Fig. 12 the said hook may be used as a stay-band. 60

I prefer to make the stay-band on the mast detachable, so that the entire rig may be lowered to the deck and stored away until needed, and when needed the said rig may be quickly put in place; but I do not desire 65 to limit myself in this respect, as the said stay-band may be made fast or permanent on the mast, and the stays connected with it made detachable from it.

In my improved rig the sails are bent or 70 secured to the usual rings o', (see Fig. 1,) so that the sails can be quickly put in place by slipping the stay through the rings.

In Fig. 4 the vessel (shown as a two-masted schooner) is represented as riding at a drag 75 or anchor, a small riding-sail f being shown as secured on a stay rod or rope f', fastened to the hook form of stay-band, as above described. The stay-band is placed on a stay rope or rod, which may be the topping-lift f⁵. 80

Instead of the particular form of stay-band shown in Fig. 7, I may use the form of stay-band shown in Fig. 12.

In Figs. 1 and 7 I have shown the yard as secured to the stay-band on a stay; but the 85 said yard may be secured to the stay-band on the mast, as shown on the foremast in Fig. 1.

I claim—

1. The combination, with a vessel and its 90 rig, of an independent stay-band and stay secured to said stay-band, and to which a storm-sail independent of the ship's regular rig may be bent or secured, substantially as described. 95

2. The combination, with the mast of a vessel, of a stay-band encircling the mast and a stay secured to said stay-band, substantially as described.

3. The combination, with the mast of a vessel, of a detachable stay-band encircling the mast and a stay secured to said stay-band, substantially as described. 100

4. The combination, with a vessel and its rig, of an independent stay-band and a yard 105 secured to or suspended from said stay-band, substantially as described.

In testimony whereof I have signed my name to this specification in the presence of two subscribing witnesses.

ALVIN F. PAIN.
